(57) **CLAIM**

The ornamental design for a foldable work light, as shown.

DESCRIPTION

FIG. 1 is a front elevational view of a foldable work light showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevational view in opened state;

FIG. 10 is a rear elevational view in opened state;

FIG. 11 is a left side view in opened state;

FIG. 12 is a right side view in opened state;

FIG. 13 is a top plan view in opened state;

FIG. 14 is a bottom plan view in opened state;

FIG. 15 is a perspective view in opened state; and,

FIG. 16 is another perspective view in opened state.
